UNITED STATES PATENT OFFICE

EDWARD B. DONOVAN, OF SPIRIT LAKE, IOWA

HEART TROCAR

Application filed December 18, 1929. Serial No. 414,958.

The object of my invention is to provide a heart trocar which is simple, durable and comparatively inexpensive to manufacture.

More particularly, it is my object to provide a heart trocar for the use of embalmers when aspirating blood from the heart of a deceased person, the trocar having several advantageous features whereby the heart may be effectively punctured without the possibility of erroneously puncturing it at a wrong point on its surfaces with the consequent result that the heart is not properly aspirated and the face of the person may become blackened from such improper aspiration.

Still a further object is to provide a heart trocar comprising a tubular casing having an end in the shape of a truncated cone with a pointed rod slidably mounted therein so that the point thereof can be entirely housed within the tubular casing, or can be extended beyond the end thereof as desired.

A further object is to provide stop means so that the point on the rod can be positively held in retracted or extended position as desired.

With these and other objects in view my invention consists in the construction, arrangement and combination of the various parts of my device, whereby the objects contemplated are attained, as hereinafter more fully set forth, pointed out in my claim and illustrated in the accompanying drawings. Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawings in which:

Figure 1 is a side elevation of my improved type of heart trocar, illustrating it diagrammatically in connection with an aspirating outfit.

Figure 2 is an enlarged sectional view of the same showing it diagrammatically piercing the thoracic cavities of a body with the point extended for this purpose.

Figure 3 is a side elevation of the trocar with the point retracted as when feeling over the surface of the heart for the proper point to insert the trocar into the heart.

Figure 4 is a side elevation illustrating the trocar piercing the heart and showing in dotted lines a hose connection used in the aspirating process.

Figure 5 is a perspective view of the outer end of the tubular casing and of the pointed rod showing constructional details and

Figure 6 is an enlarged detailed sectional view through the point of the trocar.

On the accompanying drawings I have used the reference numeral 10 to indicate the tubular casing of my trocar. The inner end of the casing 10 is in the shape of a truncated cone as indicated at 12 which might be called "tapered". The outer portion 14 of the casing 10 is shaped to receive a suction hose 16.

Within the bore of the tubular casing 10 I provide a rod 18, slidably mounted relative to the casing and having a pointed end 20.

The opposite end of the rod 18 is provided with a knob 22. Cut in the portion 14 of the tubular casing 10 is a shallow slot 24 and a deep one 26 radially opposite each other. A lug 28 is formed on the rod 18 below the knob 22 for selective coaction with the slots 24 and 26.

Practical operation

In the operation of my improved trocar for aspirating blood from the heart, the device is adjusted as shown in Figure 2 with the lug 28 coacting with the deep slot 26. In this position the point 20 of the rod 18 extends beyond the tapered end 12 of the tubular casing 10 as shown in Figures 2 and 6. When so adjusted the trocar is adapted for piercing the epidermis 30 for extending through the thoracic cavity 32 of the body toward the heart 34.

As soon as the point is received within the thoracic cavity the rod 18 is withdrawn and given a half turn and the lug 28 is then caused to coact with the shallow slot 24 as shown in Figure 3.

In this adjustment the trocar presents a blunt point to the heart 34 so that the surface of the heart can be engaged and the trocar

manipulated to determine the exact position of the heart without danger of piercing it prematurely. In this connection it may be mentioned that heretofore heart trocars have been used and feeling for the heart entails danger of prematurely puncturing it in the wrong place with the deplorable result of improperly aspirating the blood from the heart. It is necessary to pierce the right auricle of the heart and by determining the position of the heart with the trocar bluntly adjusted, the inner end of the trocar may be moved to the proper position for puncturing. The knob 22 is then manipulated for again extending the point 20 as shown in Figure 4, whereupon the heart may be punctured.

The tubular casing 10 is now left in the position shown in Figure 4 and the rod 18 withdrawn whereafter the suction hose 16 is applied to the portion 14 of the casing 10 and the aspirating process started.

Figure 1 illustrates how the aspirating process is accomplished. A container 36 having a "gooseneck" fitting consisting of a cork 38 and straight tubes 40 and 42 therethrough is used. A second suction hose 44 is applied to the tube 42 and connected with the intake side of an air pump 46 whereby a vacuum 30 may be created within the container 36 and the blood may be withdrawn from the heart and will collect in the container 36.

The aspirating process, of course, is well known to embalmers and funeral directors, but my improved two part trocar is a substantial improvement over trocars now on the market.

Some changes may be made in the construction and arrangement of the parts of my heart trocar without departing from the real spirit and purpose of my invention, and it is my intention to cover by my claim, any modified forms of structure or use of mechanical equivalents, which may be reasonably included within their scope.

I claim as my invention:

In a heart trocar, a tubular casing, a pointed rod slidable relative thereto and removable therefrom and coacting stop means on the casing and rod for selectively positioning the point of said rod entirely within said casing or extending beyond the end thereof, said stop means comprising a pair of slots of different depths and a lug slidable to position within either of said slots selectively.

Des Moines, Iowa, December 9, 1929.

EDWARD B. DONOVAN.
